ROAD AND RAILWAY CAR

George T. Ronk, Lanark, Ill.

Application January 23, 1935, Serial No. 3,163

13 Claims. (Cl. 105—215)

This invention pertains to improvements in train equipment and more particularly to that type of equipment employing cars adapted to be easily converted to either road or railway use, 5 wherein a loaded car may be drawn over a road or highway by means of an ordinary auto truck to a convenient railway station or switch, and then transferred to a railway track and operatively connected in an ordinary railway train and 10 transported to the nearest railway station or switch to the desired point of delivery for loading, after which the loaded car may then again be transferred to the highway and moved to the desired point of delivery, after which the car may be 15 unloaded. By this means the necessity of separate trucking operations to and from the railway track are eliminated, together with the expense of transferring the load from the truck to the railway train and, thence, from the railway train 20 again to the truck.

Several distinct types of road and railway cars have been designed, all of which are at the present time being experimented with. One type of the cars provides two sets of wheels at each end of 25 the car, one set employing flanged wheels for railway transportation, and the other set employing pneumatic wheels for highway transportation, with means for elevating and lowering one set of the wheels relative to the other set, 30 whereby either set of wheels may be operatively brought into engagement with the rails of the railway system or the pavement of the highway system. This form of equipment will be distinguished from the other form by use of the term 35 "convertible wheel type."

The other type of equipment employs a set of highway wheels at one end of the car and a set of railway wheels at the other end of the car, or the cars may be provided with either highway 40 wheels at both ends of the car or railway wheels at both ends of the car. One end of the car, however, is designed to be carried by the rear end of the preceding car, whereby the car is drawn as a semi-trailer with the front wheels supported 45 above the traction surfaces. This type of cars will be distinguished from the convertible wheel type by the term "articulated car, or units."

In coupling the articulated cars into a train it is necessary to elevate the front end of the 50 car and to support or carry said front end with the front wheels above the traction surface. It is also essential to provide coupling means wherein the articulated car may be either coupled to a standard railway car equipment or to a preceding articulated car. When the coupled car

is being carried as a semi-trailer or articulated car, the coupling element of said articulated car will be elevated higher than is necessary in the standard coupling equipment.

It is, therefore, one of the objects of my invention to provide in train equipment a carrier element which may be supported by the rear end of a car and moved from an inoperative position to an operative position for carrying the weight of the front end of the following car, and to provide 10 the forward end of the following car with a rider element which may be moved from an inoperative position to an operative position, designed to be supported by the carrier element, and to provide in connection therewith coupling means 15 which may be used either in an articulated train or in a train using standard coupling, the means for carrying and supporting the weight of the articulated cars being adapted to move to inoperative position at the time the cars are coupled in the manner as used in the standard train 20 equipment.

In this connection, it is further the object of my invention to provide power operated means wherein the forward end of the semi-trailer may 25 be lifted to position where it will be supported above the carrier end of the preceding car in such a manner that two cars may be coupled in the same manner as utilized in coupling the ordinary trains, simply by backing the preceding 30 car towards the car to be coupled, in which case the standard automatic coupler may be utilized. The elements or members for carrying the weight of the forward end of the succeeding car will be referred to as "sill heads."

In order that a certain amount of lateral movement of the rider sill head relative to the supporting sill head may be permitted when the standard coupled is utilized, it is another object of my invention to provide improved anti-friction means for permitting comparatively free pivotal movement of one sill head relative to the other, and at the same time provide means for retarding free lateral movement of one sill head relative to the other, as would be permitted in the ordinary coupling device, to stabilize the laterally swinging movement of the forward end of the car when used in articulation or as a semi-trailer.

A further object of my invention is to provide 50 in a sill head construction adapted to be used in connection with articulated trains, means for locking the sill head either in its inoperative or in its operative position.

A further object of my invention is to provide 55

- in railway equipment an improved coupler which may be mounted in the car frame, having coupling elements of the type such as ordinarily now in common use, wherein the said coupling elements may be moved to a number of elevated positions, and in connection therewith, improved means for elevating and lowering the said coupling elements and for locking them in the various operative elevated positions.
- 10 A further object of my invention is to provide in car equipment of either the convertible wheel or articulated type, improved means for detachably supporting the wheel carrying axles to the car frame, wherein the car may be easily and quickly converted to meet various kinds of road conditions and wherein a broken or wrecked axle or wheel support may be easily and quickly replaced by a repaired or new axle construction.
- 15 A further object is to provide in car equipment particularly of the convertible wheel or articulated type, improved axle equipment wherein a certain amount of lateral movement of the car is permitted relative to the axles, and in connection therewith, means for yieldably limiting the said lateral movement to eliminate lateral shocks as transmitted from the wheels to the car body.
- 20 A further object is to provide in a road and railway car, improved axle construction wherein the wheels carried thereby are of the dirigible type and wherein the axles are of the convertible type, and in connection therewith, improved means for elevating and lowering one of the axles relative to the other, and for steering the dirigible wheels.
- 25 A further object is to provide in a road and railway car, axle supporting pedestals and an axle housing slidably mounted in the pedestals, and within the axle housing an axle capable of movement up and down therein wherein either set of the wheels carried by the axle and axle housing may be brought into engagement with the traction surface, and further in connection therewith, improved means for pivotally connecting the wheels to their respective axle and axle housing to permit them to swing about a common vertical axis, wherein the wheels may be dirigibly operated.
- 30 A further object is to provide in a road and railway axle construction of the convertible wheel type, improved latching means for locking one of the axle elements in elevated or lowered position relative to the other axle element.
- 35 A further object is to provide in a road and railway car equipment employing adjustable sill heads of the carrier and rider type, and employing power operated means for moving the sill heads whereby the rider sill head may be elevated and supported on the carrier, additional power operated means for elevating and lowering the car frame relative to the traction surface.
- 40 My invention consists in the construction, arrangement and combination of the various parts of the device, whereby the objects contemplated are attained, as hereinafter more fully set forth, pointed out in my claims, and illustrated in the accompanying drawings, in which:
- 45 Figure 1 illustrates a portion of a car frame in transverse section and my improved convertible and dirigible axle construction as applied thereto, one end of the axle construction, together with the wheels carried thereby, being shown in vertical section.
- 50 Figure 2 is a sectional view taken on the line 2—2 of Figure 1, showing one end of the car frame in side elevation and the manner in which my improved adjustable sill head is connected there-

to, and also the manner in which the rider sill head is carried by the carrier sill head.

Figure 3 is a plan view of my improved convertible and dirigible axle construction, with the wheels removed, one end of the axle housing and the wheel supporting hub being shown in section.

Figure 4 is a plan view of my improved adjustable sill head as removed from its supporting frame, together with the adjustable sill head spider.

Figure 5 is a detail sectional view taken on the line 5—5 of Figure 2.

Figure 6 is a side elevation of the sill head spider.

Figure 7 is a transverse sectional view taken on the line 7—7 of Figure 2.

Figure 8 is a detail sectional view taken on the line 8—8 of Figure 10.

Figure 9 is a detail sectional view taken on the line 9—9 of Figure 10.

Figure 10 is a plan view of one end of the center sills of the car frame showing the manner in which my improved sill head construction and coupler device are applied thereto.

Figure 11 is a detail sectional view taken on the line 11—11 of Figure 10.

Figure 12 is a plan view of my modified form of axle construction showing the manner in which the said axle is permitted to move laterally of the car frame, and the means for cushioning the lateral movement.

Figure 13 is a detail sectional view taken on the line 13—13 of Figure 12.

Figure 14 is a detail sectional view taken on the line 14—14 of Figure 12.

Figure 15 is a detail sectional view taken on the line 15—15 of Figure 14.

Figure 16 is a detail sectional view of the modified form of axle housing showing the manner in which the lower open end of the housing is braced and the manner in which the axle locking device is mounted therein.

Figure 17 is a perspective view of the axle lock retaining plate as used in connection with the modified form of axle and axle housing.

Figure 18 is a diagrammatical view showing the side elevation of a highway tractor truck and the manner in which an articulated car is connected therewith.

Figure 19 is a diagrammatical view showing the manner in which two cars employing convertible wheel axles may be coupled in an articulated train by means of the power device as applied to the adjustable sill heads.

Figure 20 is a diagrammatical view illustrating the manner in which the forward end of a car employing convertible axles and a power operated jack device for elevating the forward end of said car whereby the rider sill head may be placed on top of the carrier sill head of the preceding car, either as used in connection with the power mechanism as applied to the sill head or in connection with a sill head in which no power mechanism is employed, and also the manner in which the adjustable car coupler of the forward car is moved to an elevated position in alignment with the car coupler carried by the rear car and supported in a normal position, wherein both coupler elements are in horizontal alignment when the cars are coupled in articulation.

Figure 21 is a diagrammatical view showing the manner in which cars having convertible axles may be coupled by means of standard car cou-

plers, and the manner in which the adjustable sill heads are moved to inoperative position.

Figure 22 is a diagrammatical view illustrating the manner in which an articulated car may be carried by a railway engine in which is employed a modified form of carrier sill head device, the figure also illustrating the manner in which different types of supporting wheels may be provided when the car may be adapted to meet various road conditions.

Figure 23 is a detail sectional view of the annular wheel support taken on the line 23—23 of Figure 3.

Referring to Figures 1 and 2 of the drawings I have used the reference numeral 10 to indicate a pair of centrally arranged, spaced and parallel sill members, these sill members being supported longitudinally and centrally of the car frame 11 carried thereby. The details of this car frame 20 are not illustrated inasmuch as they form no part of my present invention, the car body being carried by the said frame 11.

The said sill members 10 substantially form a draw bar extending longitudinally beneath the car body, wherein the strains imparted to the car body to advance the car and the series of cars connected thereto, are carried by said sill members. The sill members are also formed of such size as to have sufficient strength to over-30 come any bending strain that might be imparted thereto by elevating one end of the car by applying power to the under surface of one end of said sill members. Thus, it will be seen that the sill members not only are capable of transmitting the entire amount of power transmitted between the engine and the rear end of a train, but are also capable of supporting the weight of one end of a car body for the purpose of placing the car in articulation, as hereinafter more fully set forth.

Supported transversely beneath the frame members 10 near each end of said frame members is a pair of I-beams 12, said I-beams being spaced apart a slight distance and rigidly fixed 45 to the beams 10. These transversely arranged I-beams 12 serve to provide a supporting frame to which the axle pedestals 13 may be connected, and for carrying the weight of the car body. Each of the said pedestal elements 13 is fixed 50 to its supporting beam 12.

Each of said pedestals comprises a plate 14 having an outwardly extending flange 15 at each edge of the top flange 16. A horizontal flange 17 is provided between the flanges 15 substantially midway between its upper and lower ends, to form a supporting plate for the upper end of a spring 18. The top member 16 is secured to the bottom flange of the beam 12. The inner member 15 is secured to a bracket 19 which also has its upper surface fixed to the lower flange of the beam 12. The brackets 19 are connected by means of an arch 20, also illustrated in Figure 13. The arch 20 and the brackets 19 are fixed together so that a rigid bracket unit is provided for supporting the pedestal members 13 against movement toward and from each other, and to prevent their lower ends from separating when forward and backward strains are imparted to the pedestal member by the axle housing member hereafter described.

Each of the pedestals 13 is provided with outwardly extending flanges 21 designed to serve as guides to slidably engage bars 22 carried on the outer surface of the axle housing 23 (see Figure 12). By this arrangement the axle housing

23 is free to move vertically between the pedestal members 13.

The lower edge of the outer surface of the side members of the axle housing is provided with laterally extending spring supports 24 (see Figures 1 and 16) the said supports 24 being designed to operate between the lower ends of the flanges 15 and to carry the lower end of the spring 18. By this arrangement it will be seen that the pedestals 13 are yieldably carried by the supports 24 and the axle housing. The said axle housing 23 is formed substantially rectangular in cross section, and is provided at each end with a pair of pivot supporting lugs 25, said lugs being designed to support a vertically arranged spindle sleeve 26, the upper and lower ends of said spindle sleeve being pivotally mounted in bearing members 27 carrying an annular wheel supporting member 28 having its outer surface provided with a bearing surface for receiving any type of standard roller bearings 29, said bearings 29 being to rotatably support a flanged car wheel 30.

Each of the annular bearing members 28 is provided with a steering arm 31, said steering arms being pivotally connected to a steering link 32a, as clearly illustrated in Figure 3.

The axle housing 23 is provided with laterally extending lugs 32, each of said lugs 32 being connected to one end of a spring 33, the opposite end of said spring being connected to one of the arms 31. In this manner, the annular supports 28 are yieldably held in alignment, thus providing dirigible mounting of the car wheels 30 to the housing 23.

Slidably mounted on the sleeves 26 is an axle 34, each end of said axle carrying a sleeve 35 for rotatably supporting the inner end of a wheel spindle 36, the outer end of the wheel spindle 36 being provided with a road wheel 37 of the automobile type, having a pneumatic tire 38, said wheel being rotatably mounted on the spindle by suitable anti-friction bearings 39. This wheel is also provided with the ordinary auto brake mechanism 40.

The inner surface of the annular member 23 is provided with vertically arranged guide blocks 41 spaced apart sufficiently to slidably receive an axle spindle 36 between them, and to permit the said axle spindle to move vertically therein. By means of the guides 41 it will readily be seen that both the axle spindle 36 and the annular bearing support 28 are pivotally mounted to a common sleeve 26, wherein both the wheels 30 and 37 are dirigibly carried by the axle housing 23 and the axle 34, respectively, wherein if the members 28 are steered, the axle spindles 36 will also be steered. Since the ends of the axle 34 are slidably mounted on the sleeve 26, it will readily be seen then that the road wheels 37 may be elevated or lowered relative to the railway wheels 30, wherein the load carried by the axle housing 23 may be applied to either the road or railway wheels, the set of wheels not in use being elevated above the traction surface.

For elevating and lowering the axle 34 I have provided a cylinder 42 above each end of the axle housing 23 and supported by a bracket 43, the lower end of the bracket 43 resting on the top surface of the top members 25, said bracket being detachably secured thereto by means of a suitable bolt 44. If so desired, the lower end of the bracket 43 may be supported on the upper surface of the arch 20, as shown in dotted lines in Figure 1, simply by detaching the bracket 43.

from the cylinder 42 and reversing the position of the lower end of the member 43, for the purpose hereinafter made clear.

Slidably mounted in the cylinder 42 is a piston 45, having a downwardly extending rod 46 extending into the upper end of the sleeve 26 and connected to a block 47 slidably mounted in said sleeve, said block being provided with a pin 48 extending through vertically arranged slots 49 in the sleeve 26 and into the adjacent end of the axle 34.

By this arrangement it will be seen that if fluid is admitted to the lower end of the cylinders 42 under pressure, then the piston 45 will be elevated, causing the axle 34 to be moved to its elevated position, as illustrated in Figure 1. If fluid is admitted to the upper end of the cylinder above the piston, then the piston will be moved downwardly wherein the axle will be carried to the bottom side of the axle housing. Thus the tire 38 of the wheel 37 will engage the ground surface and the car frame be lifted, together with the axle housing, causing the wheels 30 to be elevated above the traction surface.

For locking the axle 34 and the wheel spindle 36 in either their elevated or lowered positions of movement I have provided inwardly projecting brackets 50 which are arranged in spaced pairs at opposite sides of the wheel spindle and designed to receive a slide bar 51 between each spaced pair of brackets, the inner ends of the said blocks 51 being adapted to be moved in position below the lower side of the axle spindle 36 when the said axle spindle is in its elevated position, as illustrated in Figure 1, and to be moved in position with its inner ends above the upper surface of said axle spindle 36 when the said spindle is in its lowered position of movement, as illustrated in Figure 23.

Each of the blocks 51 is provided with an opening 52 for receiving the inner ends of a bell crank lever 53, each of the bell crank levers being pivotally connected to the bracket members 54 carried by the brackets 50. Each of said bell cranks has an outwardly extending arm 55 to which a link 56 is pivotally connected, said links extending through the inner end of the support 28 and being pivotally connected to a link 57 slidably mounted in the members 32, said links being connected by a pivot 58 supported in alignment with the sleeves 26 and transversely of the housing 23, whereby the links 56 will be permitted to swing with the member 28 as it is swung about the sleeve 26, and yet permit the rods 56 and 57 to be moved longitudinally for communicating the bell cranks 54 to move the slide blocks 51 to locking or unlocking positions. The movement of the rods 57 is accomplished by means of a slide bar 59 carried on vertical rods 60 supported on the upper surface of the housing 23, the block 59 having a laterally extending shaft 61, the outer ends of which are provided with downwardly extending links 62, the lower ends of the links 62 being pivotally connected to links 63 having their lower ends pivotally connected to the inner ends of the rods 57.

By this arrangement it will be seen that if the block 59 is moved downwardly, then the lower ends of the links 63 will be moved outwardly from each other, due to the fact that they are supported in a divergent manner, as illustrated in Figure 1, and due to the fact that the inner ends of the rods 57 are held against downward movement by the blocks 32. This movement will cause the outer ends of the arms 54 to be moved from

each other and the ends of the arms 53 to be moved inwardly toward each other, and, in turn, the blocks 51 to be moved into position either above or below the axle 36.

The block 59 is yieldably held down in its lower limit of movement by means of springs 64 carried by the upper ends of the rods 60, thus providing yieldable means for always moving the blocks 51 to locking positions and for constantly maintaining those locks in locking position. The block 59 may be elevated by means of a chain 65 connected to any suitable lever arrangement 66, such as illustrated in Figure 15 and carried by a suitable rock shaft 67.

The upper and lower surfaces of the blocks 51 are provided with grooves 68 for receiving the inner ends of pins 69 carried by the brackets 50, said pins 69 serving as guides to prevent the blocks 51 from moving longitudinally of the axle housing 23.

Any suitable piping system may be provided for supplying fluid under pressure to the upper and lower surfaces of the piston 45, such as now in common use.

The upper end of each of the cylinders 42, however, is provided with a pipe connection 70 by means of which the pressure in the upper ends of the two cylinders may be equalized so as to prevent the lifting of one end of the axle more than the other. A similar pipe connection 71 is provided for the lower end of the cylinders 42.

Thus it will be seen I have provided means whereby either the rail wheels or the road wheels may be moved in contact with the traction or supporting surfaces and wherein the line of the axle is in a vertical plane common to the longitudinal central axis of the axle housing, and means whereby both the car wheels and the road wheels are pivotally and slidably mounted about a common vertical pivot, so that perfect dirigible action can be maintained by either set of wheels, and wherein the car frame may be jacked up or elevated, if so desired, by moving the road wheel in contact with the road surface. This is of considerable advantage sometimes when coupling difficulties result due to the spring deflection caused by a load or uneven terrain or open rail switching in the coupling or uncoupling of cars.

It will further be seen that the axle housing 23 may be easily detached from the pedestals by simply elevating the car frame and permitting the axle housing, together with the bracket 40 and the cylinders 42 to be removed bodily therefrom, the brake mechanism and the fluid connections to the cylinder first being disconnected. A different form of axle housing may be easily and quickly substituted if so desired.

In Figures 4, 12, 13 and 15 I have illustrated a modified form of axle housing 72 which is also hollow and substantially rectangular in cross section, having a top plate 73 and side members 74, said housing 72 being provided with guide devices 75 adapted to co-operate with the guide devices of the pedestals 13, the top member 73 being adapted to receive the cylinder bracket 43 and the cylinder 42 as above described. The lower end of the piston rods 46 extend downwardly through openings 76 in the top member 73 and connect to blocks 77, said blocks in turn being connected to two piece bearings 78 adapted to support a tubular axle 79. The bearings 78 have shoes 80 slidably supported between the side members 74. The ends of the axle 79 are adapted to carry any standard type of car wheel, such as illustrated in Figure 22 and designated by the 75.

5 numeral 81. The wheels 81 may be removed when so desired and the axle 79 substituted with arms 82, each end of the arms being provided with auxiliary axles 83 for supporting belt wheels 84 on which the belt tread 85 may be mounted for use on swampy land.

By this arrangement the forward end of the car may be carried by the sill head 86, which is pivotally connected to the back end of the engine 87a and supported in horizontal position by means of chains 86, in which case the car is adapted for railway use. By simply reversing the car end to end the wheels 81 may be elevated and the belt tread 85 permitted to engage the ground surface, in which case the car is adapted to be moved over comparatively soft ground by means of a suitable tractor device. By this arrangement it will be seen means is provided whereby different types of axles may be easily and quickly applied to the 20 housing 72 by simply disconnecting the blocks 77 from the bearing members 78 by removing the bolts 86.

In the axle housing 72 I have provided a modified form of lock 87 which is designed to be slidably supported in brackets 88 carried by the wall members 74, as illustrated in Figure 16, the blocks 87 being operated by link devices 89 and yieldably moved to a locking position by means of a spring 90 carried by the upright bolt 91, slidably mounted in a suitable bracket 92 and operated by means of the lever 66. The locks 87 are slidably mounted in openings 93 carried in the inclined portions 94 of the top member 73, the blocks being held against upward movement by means 35 of a locking bar 95 carried by frame member 96, the sides of the frame member 96 being secured to the outer surfaces of the wall members 74. The lock bar 87 operates in a slot 97 in the top member 73, as illustrated in Figure 13. The lock bar 40 may be easily and quickly removed from the exterior, if so desired, by simply first removing the frame member 96, and with it the lug 95, after which the lock bar 87 may be lifted out through the opening 97.

45 As clearly illustrated in Figure 12, the members 22 are so positioned with relation to the side members of the pedestals 13 that a considerable amount of longitudinal movement of the axle housing 72 will be permitted with relation to the 50 said members 13. This is necessary in order to eliminate undue amount of flange wear on the wheels.

In order to cushion the shock which would otherwise result when the members 22 engaged the side members of the pedestals, I have provided on each side of the housing outwardly extending lugs 98 to which the inner ends of spring 99 are connected by means of suitable bolts 100.

Thus the springs 99 provide means for cushioning the transverse shock caused by the members 22 engaging the side members of the pedestals 13, thereby largely eliminating difficulties heretofore experienced in packing articles in the cars to prevent breakage and destruction due to the 65 violent transverse shock. It will be seen that the bottom side of the axle housing 72 is open. This is provided to permit the wheel supporting axle carried therein to be easily and quickly removed either for repair or to change the type of axle to 70 accommodate various types of supporting wheels. The changing of the axle may be easily and quickly accomplished without interfering with the mounting of the axle housing.

In order to reinforce the side member 74 of the 75 housing 72 I have provided brace members 101 to

extend transversely beneath the lower edges of the member 74, and fixed to the members 24 by means of suitable bolts 102. These members 101, of course, would have to be removed before dropping the axle from the housing. This can be 5 easily and quickly accomplished, however.

The description thus far has pertained to the axle and axle housing and to the mechanism for elevating and lowering the axle relative to its housing and to the manner in which the wheels 10 15 may be steered by having pivoted spindle members connected with the axle housing and the axles.

I will now describe my improved coupling mechanism which is adapted to be used in connection with cars to be operated in articulated trains or as semi-trailers, wherein the forward end of the car is slightly elevated and supported and carried by the rear end of a preceding car or by the tractor or engine pulling the same. 20

Referring to Figures 2 to 11, inclusive, supported between the free ends of the beams 10, I have provided a cast frame 103 comprising plates 104 fixed to the inner faces of the members 10, said plates having downwardly and forwardly 25 extending lugs 105 and connected by a cross member 106. This frame provides means for rigidly supporting the free ends of the members 10 against lateral movement toward and from each other and stiffening the frame member in 30 general. It also provides means for supporting the movable sill head hereinafter to be described.

Supported inside of the plates 104 and adjacent to the inner faces of the members 10 are plates 35 107, having vertically arranged flanges 108, said flanges being spaced apart a slight distance to form guides. Supported between the guides 108 is a coupler frame 109, said frame having lugs 110 on its outer surface to travel between the 40 guides 108 and to prevent longitudinal movement of the frame 109 and at the same time permit the frame 109 to be elevated and lowered. The outer faces of the side members of the frame 109 are each provided with a longitudinal groove 45 111 in which is slidably mounted a slide link 112. Pivotally connected to the inner end of each of the slide links 112 is a rock arm 113, said rock arms being fixed to a rock shaft 114, while the outer ends of the links 112 are pivotally connected to the rock arms 115 pivotally connected to the inner faces of the beams 10. The arms 113 and 115 are of the same length so that if the shaft 114 is rocked in a counter-clockwise direction, as illustrated in Figure 11, then the free 55 ends of the arms 113 will be moved upwardly in a counter-clockwise direction, causing the free ends of the arms 115 to also be swung upwardly and inwardly by means of the links 112. This will cause the frame member 109 to be elevated 60 to its dotted line position, as shown in Figure 11.

The inner faces of the side members of the frame 109 are provided with lugs 116, against which a plate 117 is supported, designed to engage one end of the compression spring 118, the 65 other end of said spring being supported against a plate 119 carried by the inner end of the frame 109. Slidably mounted through the plates 117 and 119 is a coupler rod 120 having its outer end pivotally connected to the coupler bar 121, 70 said coupler bar extending through the forward end of the frame 109 and to a position outwardly beyond the frame member 103, to which the train coupler 122 is connected, said coupler being of that type ordinarily used in coupling trains at 75

the present time. The outer end of the rod 120 is larger than its central portion, so that a shoulder 123 is provided for engaging the outer surface of the plate 117 when the bar 121 is moved inwardly. The rod 120 has a washer 124 designed to engage the inner surface of the plate 119 as the coupler bar 121 is moved outwardly.

By this arrangement it will be seen that the spring 118 serves as a cushion for cushioning shocks imparted to the bar 122 longitudinally thereof, either caused by coupling action of the train or at the time the train is under movement on the road, due to either jerking or breaking effect.

15 By this arrangement it will be seen that the coupler 122 may be operated in two elevated positions, the coupler being in its normal position to couple with the standard train equipment when in its lowered position of movement and 20 adapted to make coupling with the coupler element at the forward end of an articulated car connection, when in an elevated position, or, in other words, when the forward end of the following car is elevated, in a manner hereinafter 25 more fully set forth.

30 A pin 125 is provided for locking the coupler frame 109 in its elevated or lowered positions of movement, simply by inserting the pin through suitable openings provided in the coupler frame, and through openings 126 provided in the frame member 103.

35 On account of the pivotal connection between member 121 and the member 120 it will be seen that the outer end of the bar 121 and the coupling element 122 are permitted to swing laterally somewhat in order to permit a certain amount of lateral movement of the coupled end of the car, in a manner as permitted in ordinary coupling practice.

40 I will now describe the adjustable sill head which permits the car to be coupled in the usual manner or in an articulated train or as a semi-trailer.

45 Supported beneath the free ends of the members 10 and beneath the coupler device 109, I have provided what I have termed a sill head spider 127, comprising frame members 128 having at their forward ends lugs 129 (see Figure 4) designed to support pivot pins 130, said pivot pins being designed to be mounted in the lugs 105 of the frame member 103 so that the inner end of the frame 127 is adapted to be elevated and lowered, the side members 128 being designed to rest adjacent to the outer edges of the lower flanges of the members 10, as illustrated in Figure 8. The inner end of the sill head frame 127 is provided with an inwardly extending arm 131, having an opening 132 (see Figures 4 and 6). The inner end of the member 131 is provided with an upwardly extending portion 133, having an opening 134, by means of which said extending portion 133 may be pivotally connected to the link 135 carried by one end of a bell crank lever 136, said lever being pivotally connected to a suitable bracket 137 carried by the beams 12. The other arm of the bell crank 136 is pivotally connected to the link 138, which in turn is pivotally connected to one end of a lever 139, the other end of which is operatively connected with a piston rod 140 operated by an air cylinder 141. Thus, means is provided whereby the inner end of the frame 127 may be elevated by power, said frame being locked in its elevated position by inserting a pin 142 extending through suitable

openings in a bracket 143 carried by one of the frame members 12.

The sill head comprises a horizontal plate 144 adapted to be supported horizontally beneath the frame 127, having at each side edge an upwardly extending flange 145, the upper edge of each of the flanges 145 terminating in an inwardly extending flange portion 146 designed to rest above the upper edges of the side members 128, thus providing means whereby the sill head is slidably mounted longitudinally of the sill head spider, the sill head being locked at either its inner limit of movement or its outer limit of movement by means of a pin 147 adapted to pass through slots 148 carried between the side members 128 and 15 suitable holes 149 in the side members 145, the pin 147 being locked in position by means of a spring 150, which is pivotally mounted at 151 so as to swing out of the path of the head of the pin 147. The sill head plate 144 is limited against 20 outward movement or movement towards the right, as illustrated in Figures 2, 4 and 11, by means of a stop pin 152 carried by the inner end of the plate 144 engaging the inner edge of the cross bar 153 carried by the lower end of the 25 frame member 127. The plate 144 is limited against inward movement by the outer edge of the bar 153 engaging lugs 154 carried by said plate 144. The outer end of plate 144 has laterally projecting plates 155, supporting upright 30 posts 156 designed to carry pivot members 157 for supporting the conical rollers 158. The forward ends of the plates 155 terminate in upwardly extending portions 159, which in turn terminate in inwardly and upwardly extending portions 160. 35 The members 160 form inclined planes to assist in elevating the rider sill head 161 as the coupling action takes place.

The under surface of the plate 144 is beveled at 162, as illustrated in Figure 5, said beveled portion being designed to rest on the rollers 158 of the carrier sill head 163 when the rider sill head 161 is in operative position, as illustrated in Figure 2, with the coupling elements 122 of the adjoining cars coupled.

40 It will be seen by referring to Figures 10 and 11 that the coupler elements 122 are designed to rest immediately above the central portion of the outwardly extending portion of the plate 144 and between the outer ends of the flanges 145. When 50 it is desired to couple two cars in articulation, as illustrated in Figures 2 and 18, the coupler element 122 of the front car is first elevated to its upper position of movement, the inner end of the sill head spider of the back car or rider sill head 161 being first lowered to the dotted line position shown in Figures 2 and 19. The coupling element 122 of the back car is left in its normal lowered position of movement. The cars are then moved together with the outer end of the rider sill head resting above the outer end of the carrier sill head. Power is then applied to the cylinder 141 causing the inner end of the rider sill head to be elevated from an inclined position to a horizontal 55 position. This will cause the forward end of the sill head to be lowered about the pivot pins 130 as fulcrums, and the front end of the rider car to be elevated to the position illustrated in Figure 18. The pin 142 may then be inserted in the 60 openings 132 and through the openings of the member 143 locking the rider sill head in its normal position. This provides means whereby the coupled end of the semi-trailer or articulated car 65 may be easily and quickly elevated to lift the 70 75

front wheels of said car from the traction surface.

If for any reason, due to track irregularities or spring deflection, the rider sill head would not move to position above the carrier sill head, then power may be applied to the cylinder 42 to cause the wheels 38 to be lowered and the front end of the car frame to be elevated. The coupler elements 122 are then employed in the usual manner and as illustrated in Figure 2, the coupler elements serving to act as a pivot for joining the two cars together.

Inasmuch, however, as the coupler elements are permitted to have lateral movement, it will readily be seen that considerable tendency would exist for the carrier and rider sill heads to move laterally, one relative to the other. By providing the inclined portions 162 and the conical rollers 158 I have provided means for retarding this lateral movement of one sill head relative to the other, to a considerable extent, and yet permitting said movement when necessary when the cars are moving over irregular track or ground surface and when making curves. This retarding action tends to eliminate a certain harmonic lateral swinging movement of the cars, as it will readily be seen that if one of the sill heads moves laterally relative to the other, then the rider sill head must be elevated against the action of gravity which will tend to retard the said lateral movement, or, in other words, the rider sill head would have a tendency to naturally assume its lower position of movement centrally located above the carrier sill head.

In a simplified sill head construction the pivoted feature might be eliminated, together with the power mechanism connected therewith, and at the same time retain the sliding features of the sill head, in which case the cylinder 42 and the piston mounted therein might be utilized to elevate the end of the car to couple it as a semi-trailer.

If it is desired to couple two cars in the ordinary way, as illustrated in Figure 21, then each of the sill heads may be moved to its inner limit of movement by simply pulling the pin 147, sliding the sill head inwardly until the stop 154 engages the member 153, then placing the pin 147 in the other sleeve 148 near the inner end of the sill head spider, at which time the outer end of the sill head is moved to inoperative position beneath the coupler frame 109.

In order to be enabled to connect the forward end of the car to the rear end of an auto truck in the manner illustrated in Figure 18 I have provided on the under surface of the central portion of the outer end of the plate 144 a downwardly extending coupling pin 164 which is of the type designed to make connection with the coupling element 165 ordinarily carried by highway tractors of that type adapted to operate semi-trailer cars. In this case the coupler element 122 is simply permitted to rest in its normal position and forms no part of the coupling action. The sill head is operated in exactly the same manner as before described for coupling two cars equipped with carrier and rider sill heads.

In Figure 22 of the drawings I have illustrated a sill head 86 which is pivotally connected to the rear end of the engine 87, having its outer end supported by means of a chain 88 instead of the sill head spider as before described. It may be necessary to use this modified type of sill head in connection with certain types of engines and other power devices, in view of the fact that no

room is provided beneath the engine for the inwardly extending end of the sill head.

When it is desired to make normal coupling, the outer end of the sill head 86 is simply disconnected from the chain 88 and allowed to swing to a vertical position behind the traction wheel of the engine.

It will readily be seen by referring to Figures 18 to 22, inclusive, that I have provided improved axle and axle housing construction, together with improved coupling devices, wherein cars equipped with said improved devices may be adapted to operate under various working conditions either to be operated in a train in the usual manner and by means of a standard coupling, or to be operated in an articulated train having either a railway engine or a highway auto truck as motive power, or wherein the car may be operated as a semi-trailer as used in connection with either a railway engine or a highway auto truck.

Furthermore, the cars may be operated in trains employing convertible railway and highway axles coupled in the regular manner as provided in the ordinary railway practice.

It will also readily be seen that various wheel arrangements may be substituted to meet various working conditions. For instance, as illustrated in Figure 22, wheels employing belt treads may be substituted for either the railway or ordinary pneumatic road wheels, in case it is desired to operate the car over soft and spongy ground, either one or both ends of the car being provided with such equipment, the other end of the car being provided with either railway or highway wheels. The belt treads 85, which are of the detachable type, may be entirely removed, if so desired, in which case the weight of the car is supported by the wheels 84.

I claim as my invention:

1. In a road and railway car, the combination of a car frame; pedestals projecting downwardly from said frame; an axle housing mounted in said pedestals to slide vertically and longitudinally of said housing; means for limiting the longitudinal movement of said housing; yieldable means for retarding the longitudinal movement of said axle housing relative to said pedestals; an axle within said housing; and means carried by said housing for elevating and lowering said axle relative thereto.

2. In a road and railway car, the combination of a car frame; pedestals projecting downwardly from said frame; an axle housing mounted in said pedestals to slide vertically and longitudinally of said housing; means for limiting the longitudinal movement of said housing; yieldable means for retarding the longitudinal movement of said axle housing relative to said pedestals; an axle within said housing; means carried by said housing for elevating and lowering said axle relative thereto; and means for locking the axle in either of its elevated or lowered positions of movement.

3. In a road and railway car, the combination of a car frame; pedestals projecting downwardly from said frame; an axle housing mounted in said pedestals to slide vertically and longitudinally of said housing; means for limiting the longitudinal movement of said housing; yieldable means for retarding the longitudinal movement of said axle housing relative to said pedestals; an axle within said housing; means carried by said housing for elevating and lowering said axle relative thereto; means for locking the axle in either of its elevated or lowered positions of movement;

and yieldable means for moving said locking means to locking position.

4. In a road and railway car, the combination of a car frame; pedestals projecting downwardly from said frame; an axle housing in said pedestals to slide vertically in said pedestals; an axle in said housing to move vertically therein; means for locking the axle in either its elevated or lowered position of movement; and yieldable means for normally supporting the locking means in locking position.

5. In a road and railway car, an axle housing; an annular wheel support at each end of said housing; a spindle pin pivotally connecting each wheel support to its corresponding end of said housing; an axle supported longitudinally within said housing and slidably mounted on said spindle pins; a wheel spindle within each annular wheel support and pivotally connected to each end of said axle by means of said spindle pins; means for sliding the axle and its corresponding spindles longitudinally of said spindle pins; and means for locking said axle and its spindles in either of two alternative positions.

6. In a road and railway car, a frame; downwardly projecting pedestals from said frame; an axle housing supported within said pedestals and adapted to move vertically therein; yieldable means between said pedestals and said housing; a wheel support at each end of said housing; a car wheel rotatably mounted on each of said supports; a spindle pin pivotally connecting each wheel support to its corresponding end of said housing; an axle supported longitudinally within said housing and slidably mounted on said spindle pins; a wheel spindle within said wheel support and pivotally connected to each end of said axle by means of said spindle pins; a road wheel for each spindle; a lift cylinder supported above each end of said housing and carried by said frame; a piston within each of said cylinders; means for connecting each of said pistons to the corresponding end of said axle whereby the axle may be moved longitudinally of said pins and whereby the weight of the frame may be shifted to either set of said wheels; and means for locking said axle and the spindles in either of two elevated positions.

7. In a road and railway car, a frame; downwardly projecting pedestals from said frame; an axle housing supported within said pedestals and adapted to move vertically therein; yieldable means between said pedestals and said housing; a wheel support at each end of said housing; a car wheel rotatably mounted on each of said supports; a spindle pin pivotally connecting each wheel support to its corresponding end of said housing; an axle supported longitudinally within said housing and slidably mounted on said spindle pins; a wheel spindle within said wheel support and pivotally connected to each end of said axle by means of said spindle pins; a road wheel for each spindle; a lift cylinder supported above each end of said housing and carried by said frame; a piston within each of said cylinders; means for connecting each of said pistons to the corresponding end of said axle whereby the axle may be moved longitudinally of said pins and whereby the weight of the frame may be shifted to either set of said wheels; means for locking said axle and the spindles in either of two elevated positions; and yieldable means for moving said locking means to operative position.

8. In a road and railway car, a frame; downwardly projecting pedestals from said frame; an

axle housing supported within said pedestals and adapted to move vertically therein; yieldable means between said pedestals and said housing; a wheel support at each end of said housing; a car wheel rotatably mounted on each of said supports; a spindle pin pivotally connecting each wheel support to its corresponding end of said housing; an axle supported longitudinally within said housing and slidably mounted on said spindle pins; a wheel spindle within said wheel support and pivotally connected to each end of said axle by means of said spindle pins; a road wheel for each spindle; a lift cylinder supported above each end of said housing and carried by said frame; a piston within each of said cylinders; means for connecting each of said pistons to the corresponding end of said axle whereby the axle may be moved longitudinally of said pins and whereby the weight of the frame may be shifted to either set of said wheels; means for locking said axle and the wheel spindles in either of two differently elevated positions; and means for equalizing the pressure between said cylinders.

9. In a road and railway car, an axle housing; an axle extending longitudinally to said housing; a wheel rotatably mounted on each end of said housing; a wheel carried by each end of said axle; means for locking the axle in elevated and lowered positions within said housing, said means comprising a pair of slide blocks carried in each end of said housing adapted to have their inner ends moved into and out of the path of movement of said axle as it is moved from its lowered to its elevated position, or vice versa; link mechanism for moving corresponding slide blocks simultaneously toward and from each other; a spring mechanism for moving the slide blocks to locking position with the slide blocks beneath the axle when elevated, and above the axle when said axle is lowered; and means for detachably securing said axle housing to the frame of a road railway car.

10. In a road and railway car, the combination of a frame; two sets of downwardly extending pedestals carried by said frame; a hollow axle housing slidably mounted to move vertically in said pedestals; an axle supported longitudinally within said housing adapted to move vertically therein; a cylinder supporting bracket carried by each end of said housing; a bracket stand carried by said frame adapted to also carry said cylinder supporting bracket whereby the cylinder bracket may be transferred from position on said housing to position on said bracket stand at the will of the operator; a cylinder carried by each bracket; a piston for each cylinder and means for operatively connecting each piston with the corresponding ends of said axle; a railway wheel rotatably mounted on each end of said axle housing, and a road wheel mounted on each end of said axle.

11. In a road and railway car, the combination of a frame; two sets of pedestals depending therefrom; a hollow axle housing mounted to move vertically in said pedestals, the bottom side of said housing being open; an axle mounted to slide vertically in said housing; means for locking said axle at a number of vertically adjusted positions in said housing, and means for elevating and lowering the axle relative to said housing, said axle being detachably connected with said elevating and lowering means and with said housing, whereby one type of axle may be easily and quickly substituted for another type of axle without molesting the mounting and arrangement of the axle housing relative to its supporting pedestals.

and frame; a wheel rotatably mounted on each end of said housing, and a wheel rotatably mounted on each end of said axle.

12. In a road and railway car, the combination
5 of a car frame; a wheel supporting member;
means for mounting said wheel supporting member to move vertically of said car frame; an axle;
means for guiding said axle to move vertically and relative to the wheel supporting member; means
10 for locking the axle to said wheel supporting member in either of its elevated or lowered positions of movement; and yieldable means for normally supporting the locking means in locking position.

13. In a road and railway car, the combination of a car frame having vertical guides; an axle housing mounted in said guides, to slide vertically and longitudinally of said housing; means for limiting the longitudinal movement of said housing; yieldable means for retarding the longitudinal movement of said housing relative to said guides; an axle within said housing; and means for elevating and lowering said axle relative to said housing.

5

GEORGE T. RONK.
